UNITED STATES PATENT OFFICE.

PHILIP H. WITTINGTON, OF CLEVELAND, OHIO, ASSIGNOR TO THE SPARKS-WITHINGTON COMPANY, OF JACKSON, MICHIGAN, A CORPORATION OF OHIO.

DIAPHRAGM SIGNAL.

Application filed January 22, 1924. Serial No. 687,879.

- This invention relates to a new and improved diaphragm signal, and more particularly to the specific form and construction of the diaphragm thereof.
- 5 The main object of the invention is to effect a substantial saving of the material, such as steel, of which the diaphragm is formed, without materially affecting the rigidity with which the diaphragm is clamped between and secured to the edges of the diaphragm case sections.
- Further, with this construction, buckling of the diaphragm ordinarily caused by the fact that the clamping surfaces are not absolutely flat, is limited to a considerable extent by reducing the area and eliminating the continuity of the clamping surfaces.
- Further, the fact that a comparatively small area of the edge of the diaphragm 20 is clamped between the case sections permits the diaphragm to flex more easily.
- Another advantage relates to the particular disposition of the contact surfaces of the diaphragm wear-piece with respect to certain of the bolt holes through which the usual clamping bolts extend.
- Other objects and advantages relate to the details of form and construction of the apparatus, all as will more fully appear from 30 the following description, taken in connection with the accompanying drawings, in which:
- Figure 1 is an elevation of the diaphragm and front case section of the signal illustrating the clamping bolts.
- 35 Figure 2 is a longitudinal section of a portion of the signal.
- Figure 3 illustrates the method of blanking the diaphragm from a strip of sheet metal.
- 40 In general form, the signal here illustrated is of a well known type and construction embodying a rear case section —1— of dished form, and a front case section —2— of oppositely dished form, the edges or peripheries of the case sections being substantially flat and adapted to receive between them the edge of a diaphragm —3— preferably formed of sheet steel. One of the case sections, as —2—, is provided with a circumferential flange —30— that engages the edge of the diaphragm and the edge of the other case section —1— when the parts are assembled.
- In the well known construction of diaphragm signals, the edge of the diaphragm 55 is preferably separated from the clamping peripheries of the case sections —1— and —2— by means of cork or other suitable washers —4—. Clamping bolts are provided extending thru the peripheries of the 60 case sections and thru openings in the edge of the diaphragm and thru the clamping washers —4—. As here shown, four of such bolts are used in the present construction of horn, and are positioned in a special manner 65 for cooperation with the diaphragm —3—, which as illustrated, is of peculiar and novel form.
- In this particular illustration deemed peculiarly efficient for accomplishing the advantages set forth above, the diaphragm —3— is of polygonal form, in this instance octagonal with alternate sides of arcuate form, and alternate sides of straight form. The arcs of the alternate arcuately shaped 70 sides —4—, —5—, —6— and —7— are preferably as shown portions of the circumference of the same circle, such circle having a diameter substantially equal to the internal diameter of the flange —30— so that the 75 diaphragm will fit within the flange —30— with the arcuate edge portions in contact with the opposite flat edge portions of the case sections —1— and —2—. The straight sides which, as illustrated, are in the position 80 of the bases of segments of the circle of which the arcuate sides form a part, are arranged between the arcuate sections, and are numbered —8—, —9—, —10— and —11— and the straight sides —8— and —10— are 85 diametrically opposite each other, while the straight sides —9— and —11— are diametrically opposite each other, and the two diameters are preferably approximately perpendicular to each other.
- The bolt openings for the reception of the bolts —12—, —13—, —14— and —15— are positioned in a special manner to effect the most advantageous results, and as here shown, the openings for the reception of the 90 bolts —12— and —14— are formed in arcuate sides —4— and —7— adjacent the oppo-

site ends respectively of the flat side —8— and the openings for receiving the bolts —13— and —15— are formed in the arcuate sides —5— and —6— adjacent the opposite ends of the straight side —10—.

- The diaphragm —3— is further provided with an opening —17— for the reception of a positioning pin —18— rigidly carried by one of the case sections as —2—.
- 10 The diaphragm is further provided with the usual wear piece —19— which in this illustration is positioned in a novel manner in that its opposite inclined sides —20— and —21— are in alignment with the openings for receiving two oppositely disposed bolts as the bolts —12— and —15—, altho the alignment might be with the bolts —13— and —14— and this for the purpose of applying the strain produced by forced vibration of 20 the diaphragm by contact of cam —22— with wear piece —19— directly across the diameter of the diaphragm which intersects two clamping bolts so as to insure rigidity and permanent securement of the diaphragm in a 25 tight and proper manner to afford the most effective sound production.

In Figure 3, the method of blanking this diaphragm is illustrated, and it will be noted that this diaphragm may be blanked from a 30 strip —24— of substantially less width than the strip required to blank a circular diaphragm having a radius equal to the radius of the arcuate sides —4—, —5—, —6— and —7—. Further, a greater number of diaphragms can be blanked from a strip of the same length, and thus a material saving in sheet metal which is perhaps the most expensive material used in signal production, is effected.

- 40 The rear case section —1— may in the usual manner carry a casing —23— which encloses the driving parts for the cam —22—.

Altho I have shown and described a specific form and construction of device as constituting a preferred embodiment of my invention, I do not desire to restrict myself to

the exact details of form, or for instance, the exact position of the bolt holes, as various changes may be made within the scope of the appended claims.

I claim:

1. A diaphragm formed of a substantially flat piece of steel and having spaced arcuate edge portions separated by straight sides constituting bases of segments of a circle defined by the arcuate edge portions, and a plurality of bolt openings adjacent the juncture of certain of the straight sides with the arcuate edge portions.

2. In a signaling device, a diaphragm case section having a flat edge portion, a diaphragm adapted to rest against the said flat edge portion, and having arcuate edge portions of substantially the same radius of curvature, and constituting portions of a circle of a diameter substantially equal to the external diameter of the flat edge portion of said case section, said arcuate edge portions being spaced by straight portions constituting substantially the bases of segments of the circle defined by the arcuate edge portions.

3. A diaphragm formed of a steel sheet substantially in the form of a polygon with alternate edges substantially straight and bolt-receiving openings wholly within the edge of the diaphragm between the alternate substantially straight sides.

4. A diaphragm formed of a steel sheet substantially in the form of a polygon with alternate edges substantially straight and bolt-receiving openings wholly within the edge of the diaphragm adjacent the opposite ends of each of the alternate straight sides.

5. A diaphragm formed of a steel sheet of substantially octagonal form and with alternate edges substantially straight and bolt-receiving openings wholly within the edge of the diaphragm.

In witness whereof I have hereunto set my hand this 31st day of December, 1923.

PHILIP H. WITTINGTON,
